SELF DETERMINING PERIMETER

Filed March 5, 1921

2 Sheets-Sheet 2

UNITED STATES PATENT OFFICE.

HOWARD McI. MORTON, OF MINNEAPOLIS, MINNESOTA.

SELF-DETERMINING PERIMETER.

Application filed March 5, 1921. Serial No. 449,944.

To all whom it may concern:

Be it known that I, HOWARD McI. MORTON, a citizen of the United States, residing at Minneapolis, in the county of Hennepin and 5 State of Minnesota, have invented certain new and useful Improvements in Self-Determining Perimeters; and I do hereby declare the following to be a full, clear, and exact description of the invention, such as 10 will enable others skilled in the art to which it appertains to make and use the same.

This invention relates to an optical instrument and particularly to such an instrument called a perimeter which is used 15 to examine and determine the range of vision of the eye. The instrument also embodies a portion which is constructed to be used as a scotometer.

It is an object of this invention to provide 20 a perimeter which the patient can himself quickly and accurately manipulate to determine the range of vision.

It is a further object of the invention to provide a perimeter having a plurality of 25 fixed spaced meridians so that the range of vision can be universally determined without the necessity of adjusting or swinging the meridians about a center or pivot point. It is another object of the invention to equip 30 such a perimeter with a central disk constituting a scotometer which will in no way interfere with the operation of the perimeter proper.

Still another object of the invention is 35 to produce such an instrument which is nicely balanced on the supporting means, and the parts of which are especially constructed so as not to interfere with the efficient functioning of the instrument.

These and other objects and advantages 40 of the invention will become apparent from the following description made in connection with the accompanying drawings in which like reference characters refer to the same 45 parts throughout the different views, and in which,

Fig. 1 represents a view in front elevation of the instrument;

Fig. 2 is a central vertical section of the 50 same;

Fig. 3 is a partial view in elevation of the rear portion of the instrument;

Fig. 4 is a fragmentary view on an enlarged scale of one of the meridians and 55 sight objects;

Fig. 5 is a transverse section on the line 5-5 of Fig. 4;

Fig. 6 is a central vertical section through the gun sight and support therefor;

Fig. 7 is a view showing one of the 60 meridians showing the graduations thereon; and

Fig. 8 is a fragmentary view showing a modified form of the invention.

Referring to the drawings, the device comprises a supporting member 1 having at one end a depending handle 1^f of any suitable and convenient form. The member 1, at its other end, has an upstanding post 1^a and a bracket member 1^b is connected to 70 the post and has formed therein a rectangular groove 1^c. An annular rim member 2 is secured in the groove 1^c by a spaced head and countersunk screws 3. The member 2 is shown as of flat rectangular cross 75 section but it will be understood that this member may have any convenient or desired shape. A plurality of equally spaced meridian members 4 have their ends terminating and fixedly secured in the member 2. The meridians 4 curve in substantially circular form rearwardly from the member 2 and converge toward the center of an annular ring 5 and have their edges disposed in the body of said ring and rigidly clamped thereto by a retaining ring 6 held in place by suitably spaced headed screws extending therethrough and into the ring 6. It will be seen that the meridian members 4 lie in substantially the surface 80 of a sphere, the center of which is disposed a short distance inside of the rim member 2 at the center thereof. An open work cage structure is thus formed and light can 85 readily pass between all of said members 4. The meridian or rib members 4 are substantially rectangular in cross section but have small, preferably, rectangular grooves formed therein at each side thereof, as shown in Fig. 5. A plurality of sight object members 7 are constructed of flat material to 90 embrace the members 4 and have projections extending inwardly into the slots in the sides thereof. The members 7 have a portion 7^a disposed on the inner side of the members 4, which is shown as of substantially circular 95 form and these members are provided on the outside of the members 4 with suitable flat handles or finger-pieces 7^b. The members 7 are adapted to slide on the members 4 and 100

to engage the same with sufficient friction to be held in any position to which they may be moved. Preferably, there are three of the members 7 provided for each meridian and, in practice, the one farthest from the center of the ring 6 will have its portion 7^a colored white. The one adjacent to this one will have its inside surface 7^a colored red and the one nearest the center will have its inner surface colored green. The screws retaining the plate 6 in position are made sufficiently long to engage in a plate 8 which is thus secured to the inside surface of the members 4.

15 This plate, as shown in Fig. 1, is of comparatively small diameter, but there is sufficient extent of the same between the ring 6 and the edge thereof for the three members 7 to be disposed therebehind. The 20 plate 8 is marked or graduated with four lines constituting diameters thereof and arranged at equal angular distances thereon. A plurality of circles 8^a are also inscribed on the disk and suitable graduations are placed on certain of the diameters at the 25 intersection with the circles. These lines which are inscribed on this disk are finely marked thereon, the disk itself being black on its inner surface. The disk also has two oval spaced marks 8^b thereon disposed somewhat below its horizontal diameter. This disk, so marked, constitutes a scotometer, the use of which will be well understood by those skilled in the art. Extending inwardly and upwardly from each side of the bracket 1^b are rods 1^d, the vertical part of which is disposed substantially in alignment with the center of the sphere and these rods are again bent to extend inwardly 30 horizontally at their upper ends and then converge and are formed with a head member 1^e. The member 1^e is formed with a flat front surface and a gunsight member 9 is pivotally secured thereto by a headed screw extending into the said head. The member 9 is provided with a small sight aperture 9^a, the axis of which coincides with the horizontal axis of the sphere outlined by the members 4. The member 9 has a 35 small flat spring 10 secured thereto at its upper end by a rivet or other suitable fastening means, and this spring extends to the lower part of the said member and has a pin 10^a supported therein and extending through an aperture in the member 9. This pin 10^a, when the member 9 is in upstanding vertical position, as shown in Fig. 1, registers with a small aperture formed in the head 1^e to hold the member 9 in this position. The 40 engagement of the pin 10^a with the head 1^e is so slight that the member 9 can be turned on its pivot to depend downwardly from the head 1^e and will be turned in this position when the scotometer part of the instrument is used. The meridian members 4

will be designated on the rear surface of the member 6 by the letters A, B, C, etc., as shown in Fig. 3, the letter A being applied to the meridian extending vertically and the other letters successively to the ribs in a counter-clockwise direction, as seen in this figure. The outer side of the meridians 4 are graduated according to the degrees of a circle and carry designations from 10 to 90, as shown in Figs. 3 and 7. The front surface of member 2 is likewise graduated in the degrees of a circle and carries designations from zero to 330, the zero being located at the right of the horizontal diameter and the designations applied to the meridians in a counter-clockwise direction.

A modified form for holding the rim 2 is shown in Figs. 2 and 8. Instead of this member being rigidly secured in the bracket 7^b, this bracket is provided with the slot 1^c which is open at its rear end for the greater part of its width. A thumb screw 11 is journaled in the bracket and a block member 12 is fitted at the rear of the bracket 1^b having a shouldered portion engaging the lower edge of member 2 and projecting over its rear surface. The block 12 is threaded to receive the threaded end of a thumb screw 11 and the member 2 can thus be clamped between brackets 1^b and the block 12 by tightening this thumb screw. Likewise, by loosening the thumb screw, the member 2 can be adjusted angularly about its center in the bracket 1^b. With this construction, the member 2 carries graduations at its lower front portion indicating a turning movement of ten to twenty degrees to each side of its vertical axis. By having the handle portions 1^f disposed, as shown, and the member 1 projecting forwardly therefrom, the instrument is nicely balanced when held in the hand and has no decided tendency to tilt forwardly or rearwardly, it also being obvious that it is well balanced laterally. The front of the member 2, front surface of disk 8 and the front surface of the meridians 4, as well as the supporting arms 1^d, and the member 9, will all be painted black or coated with a black material. While in the embodiment of this invention illustrated, the instrument is shown provided with a handle adapted to be held in the hand of the patient, it is within the scope of this invention to support the instrument upon a fixed bracket secured either to the wall or floor of a room, which bracket will preferably be located close to a wall or screen.

The operation is as follows:

The instrument is preferably constructed, 125 as shown, to be held in the hand of a patient. The perimeter will be brought so that the aperture 9^a is substantially on a level with the eye and the member 1^d pressed against the cheek below the eye, so that the 130

eye is substantially located at the center of the sphere. The instrument is then held stationary by the patient who sights through the aperture 9^a to the central aperture in the 5 disk 8. While holding the instrument in this position with one hand, the sight objects 7 are moved outwardly on the meridians 4 until the same are just at the edge of vision. These objects will usually be 10 moved beyond the range of vision and will then be brought inwardly to a point where they can just be seen by the patient. By so positioning all of the light sight objects, it can be readily determined just what field of 15 vision the patient has. This field of vision often varies in the three colors white, red and green, and if desired, the said field can be investigated for the other colors by using the red and green sight objects. When the 20 scotometer portion of the instrument is to be used, the instrument is held in substantially the same position but the sight member 9 is then turned downwardly and the patient concentrates his gaze on the disk 8. 25 Light can readily pass between the meridians 4 so that a light back ground may be had. Also by holding the perimeter before colored screens or surfaces, any desired color of back ground may be used.

30 It may sometimes be desired to determine the range of vision with more accuracy than can be done by the meridians 4 which are spaced circumferentially at angles of thirty degrees. With the construction shown in 35 Figs. 2 and 8, the member 2 and meridians 4 can be turned circumferentially ten or twenty degrees and readings can thus be obtained on the meridians 4 with the same located at intervals of ten degrees. This 40 more accurate determination may, of course be made at any portion of the field. The spots 8^b shown on the scotometer disk are for the purpose of investigating the so-called blind spots in the eye, which, as is 45 well known, are caused by the connection or entrance of the optic nerve into the retina.

From the above description it will be seen that applicant has produced a perimeter which can be quickly manipulated by the 50 patient or oculist accurately to determine the field of vision. There are no parts that need to be revolved to various positions, as in the perimeters of the prior art, yet the instrument is light, convenient and efficient. 55 The sight objects make a good contrast against the light passing between the meridians and the device is usable in most any degree of lighting. The open work form of the device also renders it light in weight 60 so that it may be readily held in one hand and manipulated by the other. With such an instrument as herein disclosed, the patient can often quickly and accurately manipulate and adjust the instrument while 65 the oculist is performing some other duty

or attending another patient. As above indicated, the instrument may, if desired, be placed upon a fixed support and suitably disposed for the convenience of the patient.

It will, of course, be understood that 70 various changes may be made in the form, details and arrangement of the device without departing from the scope of applicant's invention, which, generally stated, consists of the matter shown and described and set 75 forth in the appended claims.

What is claimed is:

1. A perimeter comprising a plurality of spaced relatively fixed meridian members arranged in diverging relation in a substantially semi-spherical surface, sight objects 80 slidable on each of said members and disposed at the concave side thereof, the spaces between said members being open and unobstructed for substantially their entire 85 extent whereby an open-work structure is provided in which light can pass between said members.

2. The structure set forth in claim 1, a member joining the adjacent ends of said 90 members and an annular member joining the other ends of said members.

3. A self-determining perimeter having in combination a plurality of equally spaced 95 semicircular members disposed in and outlining substantially the surface of a semi-sphere the space between said members being free and unobstructed for substantially their entire extent, and disk objects movable thereon so as to be disposed and held at any 100 position throughout the length thereof whereby a cage-like structure is formed in which light can pass between said members.

4. A perimeter comprising a plurality of 105 equally spaced fixed semicircular meridian members radiating from a common point and extending laterally to one side of said point and symmetrically disposed about a horizontal axis extending through said point, sight objects movable on said meridian members, and a sight member having a sight aperture located in the said horizontal axis at some distance from said point.

5. The structure set forth in claim 4, and 110 a disk disposed at the side of said members toward the sight having its center in the horizontal axis passing through the sight aperture and said point and having a small aperture at said center.

6. The structure set forth in claim 4, a 115 disk disposed on the side of said meridian members toward the sight having its center in a horizontal axis passing through the sight aperture and said point and having a small central aperture therein, and a rim member joining the diverging ends of said meridian members.

7. The structure set forth in claim 4, a 120 disk disposed on the side of said meridian members toward the sight member having 125

130

its center in the horizontal axis passing through said point and the aperture in the sight member and having a small central aperture therein, a rim member to which the diverging ends of the meridian members are connected, and a supporting means for said rim member.

8. A perimeter comprising a plurality of fixed equally spaced meridian members disposed in and outlining substantially the surface of a semisphere, a disk member located on the inside of said members at the converging portions thereof having its central axis in the horizontal axis of said sphere and having a small central aperture therein, sight objects slideable on said meridian members and frictionally engaging the same to be held in the position to which they are moved, and a gun sight having a sight aperture located in the horizontal axis of said sphere adjacent the center of the sphere.

9. The structure set forth in claim 8, and an annular rim member connecting the diverging ends of the meridian members.

10. The structure set forth in claim 8, an annular rim member connecting the diverging ends of the meridian members, and a supporting means for said rim member.

11. The structure set forth in claim 8, an annular rim member connecting the diverging ends of said meridian members, a supporting means for said rim member disposed at the lower central portion thereof, and a handle for said supporting means disposed a substantial distance to one side of the plane of said rim member toward the converging ends of the meridian members.

12. A perimeter comprising a plurality of relatively fixed rib members angularly spaced less than ninety degree apart, and sight objects slidably mounted thereon to be retained in any position to which they may be moved.

13. A perimeter comprising a series of angularly spaced rods disposed in a substantially semi-spherical surface, an annular member connecting the outer ends of said rods, a member connecting the inner ends of said rods, the spaces between said members being substantially unobstructed, thus forming a cage-like structure, a handle member in which said annular member is mounted and circumferentially movable.

14. An instrument comprising a perimeter having a plurality of fixed spaced and diverging meridian members with open and

unobstructed spaces therebetween, a disk located centrally thereof at the converging portions and having a small central aperture therein, said disk being marked to form a scotometer and sight objects frictionally slideable on said meridian members and adapted to be moved from view in the rear of said disk.

15. An instrument comprising a perimeter comprising spaced rods disposed in the surface of the semisphere, an apertured disk member carried thereby at the center of said surface, a sight member having an aperture located substantially at the center of the sphere defined by said surface co-operating with said disk aperture, said disk constituting a scotometer, and said sight member being constructed and arranged to be moved to inoperative position when the scotometer is used.

16. A perimeter comprising a plurality of fixed meridian members radiating from a common point and projecting to one side thereof and angularly spaced less than 180 degrees apart, a member to which the inner ends of said members are connected, and an annular member to which the outer ends of said members are connected.

17. A perimeter comprising a plurality of fixed spaced meridian members radiating from a common point in planes intersecting at angles less than 180 degrees and making equal angles with a vertical plane passing through said point, and means joining the outer ends of said members.

18. A perimeter comprising a plurality of relatively fixed substantially semi-circular meridian members spaced less than ninety degrees apart, supporting means at both ends thereof, the spaces between said members and said supporting means being open and unobstructed for substantially their entire extent and said meridian members being visible from the concave side of the perimeter.

19. A perimeter comprising a plurality of rod-like members radiating from a common point and making equal angles with a vertical plane passing through said point, said members being angularly spaced less than 180 degrees apart, and an annular means connecting the outer ends thereof said members being visible from a point in the plane of and enclosed by said annular means.

In testimony whereof I affix my signature.
HOWARD McI. MORTON.
